(CL. 62—4)

This invention relates to refrigerating plants comprising reciprocating piston type compressors.

In refrigerating plants comprising piston type compressors, as a rule, an electric motor drivingly connected with the refrigerant compressor by means of a belt drive is automatically connected with or disconnected from a source of current as required by means of a relay or a 5 thermostatic regulator, for the purpose of maintaining a predetermined temperature in the refrigerator. When the electric motor is connected, the refrigerant gas is compressed in the 10 compressor and displaced into the condenser wherein it is condensed while emitting heat. In most of the practical cases submerged coil 15 evaporators are used in connection with which the compressor must produce sub-atmospheric pressure, so that evaporation of the refrigerant 20 takes place in the evaporator until the desired temperature is established and the motor is disconnected. From this it follows that the compressors operate periodically, in such manner, that a relatively long period of non-operation 25 is followed by a period of uninterrupted operation of a relatively long duration also.

With this mode of operation, the removal of the heat of condensation and superheating is restricted to a relatively short time, and, since 30 the area of the surfaces concerned (compressor cylinder and condenser) is limited, high condensation temperatures and pressures as well as high cylinder temperatures result and thus accordingly detrimental influences on the wall 35 surfaces of the compressor and condenser. Under these circumstances the degree of efficiency of non-water cooled refrigerating plants is considerably decreased. Also the presence of the belt drive and the unavoidable ventilation losses 40 attending the mode of operation above explained further contribute to decreasing the degree of efficiency of this type of refrigerating plant.

For practical reasons, such as current impulses due to cutting in of switches, and relay 45 energizing, the rating of the motor must not be chosen too high, in consequence of which a relatively high rotative speed is required for the motor, in order to obtain the necessary refrigerating effect and adaptability of the aggregate. 50 It is further known to effect the suction stroke of the compressor piston by means of the pressure of the refrigerant vapor entering the compressor and the pressure stroke of the compressor piston by means of an electric magnet, which is appropriately alternately connected and

disconnected in automatic manner, whereby the output of the compressor is automatically controlled in accordance with fluctuations of demand for refrigeration of the plant. In this way, a decrease in the energy consumption of the plant and thus a corresponding economy in the costs of operation can be obtained, but owing to the current impulses which are set up due to the cutting in of switches, the cylinder output, that is, the amount of refrigeration produced is restricted to a certain limit by the size of the electromagnet used, that is, the current consumption thereof. At the same time the abrupt movements of the compressor piston caused by the electromagnet require unduly large 10 valve openings and correspondingly large cross sectional areas of the pressure pipings used, in order to avoid excessive pressure surges.

The present invention is concerned with a refrigerating plant comprising a piston type 20 compressor the suction stroke of which is effected by the pressure of the refrigerant gas entering the compressor, whilst the compression stroke of the compressor is effected by electric energy which is automatically controlled by 25 switch means.

According to the present invention, the above-mentioned drawbacks are eliminated in that, for the purpose of effecting the pressure stroke, a 30 plunger operated device cooperating with the compressor piston is automatically locked, when the pressure of the refrigerant gas in the suction conduit is relatively low, and is automatically released, when the pressure of the refrigerant gas in the suction conduit attains a pre- 35 determined higher value, the shaft of an electric motor being rotated during the suction stroke by means of the piston rod, while the energising circuit of the motor is interrupted and the energising circuit of the motor being closed while the piston moves through the respective end portion of 40 stroke.

Therefore, since the electric motor is electrically driven only while the compressor piston performs the pressure stroke, after the motor 45 has been imparted a predetermined rotative speed by the plunger operated device, no current impulses, that is, no material current impulses set up in the electric circuit, when the electric motor is connected. The plunger operated device can be released by means of only relatively small fluctuations of pressure of the refrigerant vapor, so that the compressor can be started for continuous control of the demand on refrigeration of the refrigerating plant. In practice low 50

rotational speeds of the electric motor and thus relatively small numbers of strokes of the compressor piston may be applied, so that the compressor and condenser are prevented from heating up excessively. At the same time the heat developed is afforded ample time for dissipating, for the reason that the cycle of operation of the compressor is extended over a longer period. In this way, a very satisfactory degree of efficiency of the refrigerant compressor is obtained which is further improved due to the belt drive and the ventilation losses being dispensed with. Again, a relatively cheap electric motor can be used owing to the motor circuit being closed only after the motor has been started by action of the compressor piston. Any type of short circuit armature motor, for example, the ordinary mono-phase induction motor with short-circuited armature, is suitable.

20 The accompanying drawings serve for explaining the invention, by showing an embodiment of the same by way of example.

In the drawings,

Fig. 1 is a sectional elevation of a compressor, inclusive of accessories;

Fig. 2 is a larger scale section of a detail of the compressor;

Fig. 3 is an elevation, partly in section, taken at right angles to the plane of Fig. 1 and including the electric motor and parts of a toothed gearing;

Fig. 4 is a sectional view on the line IV—IV of Fig. 1 on a larger scale.

Fig. 5 is a sectional view taken at right angles to the plane of Fig. 4 showing a gear wheel provided with a one-way clutch, and

Figs. 6 and 7 are detail views for explaining the operation of individual movable parts.

In Fig. 1, the numeral 1 designates the condenser containing liquid ammonia, a lower conduit 2 leading from the condenser to a temperature regulating device 3 which communicates with an evaporator 4 the other end of which is connected with the upper end of a cylinder 5 forming part of a refrigerant compressor. The upper end of the cylinder 5 is further connected with the upper end of the condenser 1 through a conduit 6. The cylinder 5 is provided with a compressor piston 7 which, under certain conditions of operation, moves up and down and which is provided with a packing ring 8 (Fig. 2) serving for the removal of oil and with an apron 9 consisting of a hygroscopic material, such as felt. Above the ring 8, a collar 10 consisting of a material resistant to oil, for example, a special rubber material, is arranged on the piston 7 as well as a headpiece 11 which is situated inside of the collar so that, on the one hand, the lost space is accordingly reduced and, on the other hand, an open annular space 12 is formed within the collar (Fig. 2) which is filled with a special oil.

Above the collar 10, on the headpiece 11 of the compressor piston 7 a further packing ring 13 for oil removal is arranged, for the purpose of preventing oil leakage in the direction towards the cylinder head, that is, towards the pressure side for the vapor. The apron 9 of the compressor piston 7 dips each time, when moving downwards, into an oil supply 14 present in the closed lower end of the cylinder 5, thereby absorbing oil for lubricating the cylinder 5. The lower packing ring 8 on the compressor piston 7 also prevents the passage of an excess of oil. Owing to the oil within the cylinder having the tendency to flow downwardly to the most part, the supply of oil

within the collar 10 remains substantially constant, so that the latter is properly lubricated at all times.

At the lower end of the cylinder 5 a vent pipe 15 is arranged. In the head of the cylinder 5 spring loaded valve disks 16, 17 are correlated to the port openings of the connecting conduits to the evaporator 4 and the condenser 1 respectively (Fig. 2). The two valve disks 16, 17 are displaceably arranged in associated recesses in the upper head of the cylinder 5, so that the disks can open and close in response to corresponding pressure influences. The valve seats 16a, 17a, which consist of rubber, ensure that the respective port openings are tightly sealed against leakage of ammonia.

To the lower end of the guide rod 18 of the compressor piston 7 is pivotally connected a rack 19 which forms an extension of this rod and is provided with oppositely disposed toothed portions 20, 21. These toothed portions cooperate with pinions 22, 23 respectively. The pinion 22 is arranged on a shaft 24 with which it is connected by a one-way clutch 25 (Figs. 4, 5) so as to be driven by this shaft in one direction of rotation only, namely while the compressor piston 7 moves downwardly; thus by means of the rack 19. The pinion 23 is freely revolvably arranged on a shaft 26 (Fig. 4). The hub 23' of the pinion 23 provides one portion of a claw clutch and can be moved into engagement with a second portion 27 of this clutch which rotates together with the shaft 26.

To this end the pinion 23 is provided with a circumferential groove which is formed in the hub thereof and which is engaged by a slot guide on a clutch control lever 28 which is mounted on a bolt 29 and carries a roller 30, at its outer end. The clutch control lever 28 cooperates, by means of the roller 30, with a cam slot 31 (Figs. 4, 6 and 7) which is provided with two oblique ascending faces 32, 33 and is formed by a projection 34 arranged on a side of the rack 19 which is devoid of gear teeth. The projection 34 is further provided with a guide face 35 (Figs. 6 and 7) which joins with an oblique face 36 to which a switching member 37 is correlated.

A lever 38 cooperates with the faces 35, 36 and the switching member 37 by means of a perpendicularly bent up arm, this lever being mounted at 39 and is connected to a mercury tumbler switch 40 and influenced by a tension spring 41. The switch control lever 38 provides the armature of an electromagnet 42 one terminal of which is connected to the tumbler switch 40 by a lead, as shown in Fig. 3. The second terminal of the tumbler switch 40 is connected to an electric motor 44 by a lead 43 (Fig. 3), further leads 45, 46 and 47 being associated with this motor, and a branch conductor 48 extending between the latter and the electromagnet 42, whereas the numerals 46, 47 designate line conductors of the network. The energizing circuit of the electric motor 44 is closed or broken by means of the tumbler switch 40 depending upon conditions of operation.

To the shafts 24, 26 are secured gear wheels 49, 50 respectively both of which are in mesh with an intermediate wheel 51 (Fig. 1). To the shaft 52 carrying the intermediate wheel 51 is secured a gear wheel 53 which meshes with a pinion 54 which is fixed to the shaft 55 of the electric motor 44.

A locking bar 56, which is rockably mounted on a pivot bolt 57, cooperates with the rack 19

of the compressor piston 7. A tension spring 58 tends to retain the locking bar 56 in the position shown in Fig. 1 in which this bar engages into a recess in the lower end of the rack 19, by means of a roller. A spring-loaded auxiliary lever 59 cooperates with the locking bar 56 by means of a bent up end and interengages at the other end with a fork on a movable contact member 60 which is correlated to a stationary contact member 61. The contact member is arranged at the end of an elastic bellows 62 which can expand in the direction of its longitudinal axis in a manner known per se, the other end of the coil communicating with the piping of the evaporator 4 through a conduit 63. The locking bar 56 is provided with a lateral projection 64 which provides the armature of an electromagnet 65 which is connected by a lead 66 with the stationary contact member 61, the second lead 67 of this magnet being connected to the line conductor 46 of the supply circuit. A lead 68 connects the movable contact member 60 to the line conductor 47 of the supply circuit.

The operation is as follows:

25 The plant is assumed to be in the condition of non-operation as depicted in Fig. 1. If, for example, the refrigerator cabinet is opened and consequently the temperature rises in the same, the temperature regulating device 30 3 allows liquid ammonia to pass from the condenser 1 into the evaporator 4 so that the ammonia present in the evaporator begins to vaporize, due to this heating effect and the normal pressure of less than two atm. existing in the evaporator. By action of the pressure rise thus setting up in the conduit 63, the elastic bellows 62 is accordingly expanded, that is, elongated, in the direction of its longitudinal axis, so that the movable contact member 60 contacts 35 with the stationary contact member 61. Consequently, the electromagnet 65 is energized by current from the line 46, 47 of the circuit through the leads 66, 67 in which way the lateral projection 64 of the locking bar 56 is attracted so 40 that the latter is rocked away from the rack 19 of the compressor piston 7.

45 By this means the rack 19 and the path of movement of the same is cleared by the locking bar 56, whereupon the compressor piston 7 is 50 moved downwardly, by pressure action of the refrigerant gas passing from the evaporator 4 onto the piston and face through the valve 16, then opened, of the cylinder 5, and the rack 19 is moved downwardly together with the piston. 55 This downward movement of the rack 19 is not obstructed by the pinion 23 for the reason that this pinion 23 is now moved out of engagement with the clutch portion 27 by the clutch control lever 28, due to this lever having been correspondingly adjusted during the preceding upstroke of the compressor piston 7 by means of the cam slot 31 of the rack 19, as will be hereafter more explicitly explained. On the other hand, the shaft 24 is rotated counterclockwise, 60 with reference to Fig. 1, during this downward movement of the rack 19, by the pinion 22 by means of the clutch 25 then being operative.

65 Therefore, the shaft 55 of the electric motor 70 44 is rotated from the shaft 24 through the intermediary of the gear wheels 50, 51, 53 and 54 at a speed which depends upon the pressure of the refrigerant acting on the compressor piston 7 and accordingly reciprocating the piston 75 at a corresponding speed. The motor is not con-

nected at this time. Prior to the rack 19 arriving at its lowermost position the switch control lever 38 slides along the oblique face 36 provided on the projection 34, whilst this lever is rocked against the action of the spring 41, so that the mercury tumbler switch 40 is tilted, in such a way, that contact is established between the two terminals of this switch and thus the energizing circuit of the motor is closed through the leads 47, 48, 43, 45 and 46, in consequence of which, the mechanical driving of the motor is changed over to electrical driving.

During the downward movement of the rack 19, shortly before arriving at its lowermost position, the oblique ascending face 33 of the cam slot 31 effects a rocking movement of the clutch control lever 28 to the right (Fig. 4) so that the clutch portion of pinion 23 is moved into interengagement with the clutch portion 27 and the pinion 23 is thus operatively connected for rotation with the shaft 26 which is rotated from the intermediate wheel 51 by the gear wheel 49. By the rotational movement, thus imparted to the pinion 23 from the electric motor 44, the rack 19 is moved upwardly. This upward movement 25 of the rack 19, and consequently also that of the compressor piston 7, is not opposed by the pinion 22 which is now free to rotate in the opposite direction from before. Due to the fact that the clutch 25 is now ineffective, the pinion 20 22 can freely rotate about the shaft 24.

During the upward movement of the compressor piston 7 the latter cooperates with the condenser 1 via the valve 17, then opened, of the cylinder 5. Accordingly, the rack 19 is moved upwardly whilst the switch control lever 38 slides over the switching member 37 then held in closed position, for example, by a leaf spring, and over a guideway 37' forming an extension of the switching member (Figs. 6 and 7). The switch control lever 38 moves clear of the guideway after the rack 19 has passed through approximately half the upstroke, the switch control lever 38 being, however, prevented from rocking back under the influence of the associated spring 41, 45 due to the force of attraction of the magnet 42 having been increased sufficiently, by an increase of the motor current, in the meantime, on account of the loading of the motor, for retaining the switch control lever 38 in position.

50 When the compressor piston 7 has completed the compression stroke, the rack 19 is at its uppermost position, whilst the clutch control lever 28 has been rocked by the ascending face 32 of the cam slot 31, in such manner, that the pinion 23 is moved out of engagement with the clutch portion 27. Consequently, the rotative connection between the pinion 23 and the shaft 26 is interrupted. As, at this time, the motor is relieved, the motor current is decreased instantaneously, in consequence of which the attractive force of the magnet 42 is accordingly decreased, whereupon the switch control lever 38 is retracted from the electromagnet 42, by action of the spring 41, and the mercury tumbler switch 40 is 60 disconnected, so that the motor circuit is interrupted. Provided that the pressure in the evaporator 4 is still sufficiently high, the operation 65 described will be repeated, whereby the motor is, at first, mechanically driven, namely, during the downward movement of the compressor piston 7, whereas during the upward movement, that is, during the compression stroke, the piston is driven electrically.

70 While the condition of operation described is 75

maintained, the pressure of the refrigerant gas is naturally decreased. Under the influence of this pressure, the elastic bellows 62 is contracted so that the auxiliary lever 59 is accordingly rocked 5 against the influence of the associated spring. This lever 59 was previously, that is, after the locking bar 56 had been swung out of operative position, so rocked that by means of its upwardly projecting arm the locking bar 56 is secured 10 in inoperative position.

As the auxiliary lever 59 rocks back into initial position, the locking bar 56 swings back into operative position by action of the tension spring 58, for subsequently to obstruct the downward 15 movement of the rack 19 and that of the compressor piston 7, at the same time, until the pressure of the refrigerant gas has risen to such an extent that the elastic bellows 62 is sufficiently expanded for moving the associated contact 20 member 60 into contact with the stationary contact member 61, whereupon the electromagnet 65 is again energised and the locking bar 56 is rocked out of operative position. In this way the whole sequence of the further operations, 25 previously explained, is initiated.

Various changes and modifications may be made in the practice of my invention without departing from the principle or spirit thereof, by adding customary practice and established 30 knowledge of the art to the present disclosure, and the scope of the appended claims is not to be regarded as limited except as specified therein.

I claim:

1. In an automatic refrigeration system, an 35 evaporator, a condenser, a compressor having a reciprocable piston, a driving motor, a power transmission mechanism connecting the motor with said piston to drive the piston in the direction of its compression stroke, means for locking 40 said transmission mechanism in such position as to hold said piston in a position removed from its extreme end position of compression, means responsive to the pressure of the refrigerant gas at the suction side of the compressor for controlling 45 said locking means to effect locking when said pressure is below a predetermined pressure and to release said piston when the pressure exceeds a predetermined pressure, the suction stroke of the piston being then effected by the 50 pressure of the refrigerant gas, and the rotation of the driving motor being initiated by the action of the piston, and means for automatically connecting said motor with a source of electric power after the piston has initiated its rotation, whereby the motor drives the compressor during 55 its compression stroke.

2. Apparatus according to claim 1 and in which the means for controlling the locking means comprises an electro-magnet and an electric switch 60 for controlling the electro-magnet.

3. Apparatus according to claim 1 and in which the means for controlling the locking means comprises an expansible device connected with the system on the suction side of the compressor, an electro-magnet, and an electric switch for controlling the electro-magnet.

4. In an automatic refrigeration system, an evaporator, a condenser, a compressor having a reciprocable piston, a driving motor, a power 65 transmission mechanism connecting the motor with said piston to drive the piston in the direction of its compression stroke, a pivoted lever for locking said transmission mechanism in such position as to hold the piston in a position in its expansion stroke spaced from its extreme end

position of compression, a second pivoted lever for latching the first-mentioned lever in piston locking position, an electro-magnet, a switch for controlling the circuit of said magnet, said piston locking lever being within the field of influence of the electro-magnet, means responsive to the pressure of the refrigerant gas at the suction side of the compressor for closing the switch of the electro-magnet and for turning said latching lever to releasing position when said pressure exceeds a predetermined pressure, and for opening said switch and pivoting said latching lever to piston locking position when said pressure falls below a predetermined pressure, whereby when the piston is released the suction stroke of the piston and corresponding rotation of the motor are initiated by the pressure of the expanded refrigerant gas, and means controlled by the movement of the piston in its suction stroke for connecting the motor with an electric circuit so that the piston is driven by the motor in its compression stroke.

5. In an automatic refrigeration system, an evaporator, a condenser, a compressor having a reciprocable piston, a driving motor, a power 25 transmission mechanism connecting the motor with said piston to drive the piston in the direction of its compression stroke, means for locking said transmission mechanism in such position as to hold said piston in a position spaced from 30 its extreme compression end position, means responsive to the pressure of the refrigerant gas at the suction side of the compressor for controlling said locking means to effect locking when said pressure is below a predetermined pressure and 35 to release said piston when the pressure exceeds a predetermined pressure, the suction stroke of the piston being then effected by the pressure of the refrigerant gas, and the rotation of the driving motor being initiated by the action of the piston, and means including a mercury switch, an electro-magnet, a shift lever under the influence of said magnet and in position to be actuated upon inward movement of the piston, whereby the piston in its inward movement actuates the shift lever to move the mercury switch to closed position to close the circuit through the motor to drive the piston in its compression stroke, the electro-magnet being strongly energized by the current of the motor during the compression stroke so as to hold said shift lever and switch in closed position, the current drawn by said motor being reduced upon completion of the compression stroke and the electro-magnet being correspondingly de-energized so that the shift lever and mercury switch are released and the switch is opened and the motor circuit thus broken.

6. In an automatic refrigeration system, an evaporator, a condenser, a driving motor, a compressor to be driven in its compression stroke by said motor, said compressor having a cylinder, a piston provided with an oil stripper ring extending therearound and with a sleeve below said ring, said sleeve having an annular oil chamber 65 formed therein, a power transmission mechanism connecting the motor with said piston to drive the piston in the direction of its compression stroke, means for locking said transmission mechanism so as to hold said piston in a position 70 spaced from its extreme compression end position, means responsive to the pressure of the refrigerant gas at the suction side of the compressor for controlling said locking means to effect locking when said pressure is below a 75

predetermined pressure and to release said piston when the pressure exceeds a predetermined pressure, the suction stroke of the piston being then effected by the pressure of the refrigerant gas, 5 and the rotation of the driving motor being initiated by the action of the piston, and means for automatically connecting said motor with a source of electric power after the piston has initiated its rotation, whereby the motor drives 10 the compressor during its compression stroke.

7. Apparatus according to claim 1 and in which the compressor is provided with an inlet and an exhaust valve each having a rubber seat.

8. Apparatus according to claim 1 and in which the compressor has a piston provided with a downwardly extending apron of hygroscopic material, and the compressor has a cylinder provided with an oil reservoir in which the apron 5 is immersed at the lower portion of the piston stroke, so that oil is raised by the apron and distributed over the walls of the cylinder upon upward movement of the piston.

10
OTTO ZEHNDER.
